FIG. 5.

UNITED STATES PATENT OFFICE.

MORRIS W. POOL, OF BROOKLYN, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 852,799.

Specification of Letters Patent.

Patented May 7, 1907.

Application filed October 8, 1906. Serial No. 338,006.

To all whom it may concern:

Be it known that I, MORRIS W. POOL, a citizen of the United States, and a resident of Brooklyn, in the county of Kings and State of New York, have invented certain new and useful Improvements in Type-Writing Machines, of which the following is a specification.

My invention relates more especially to ribbon mechanism for typewriting machines and it has for its main object to provide an improved construction wherein a ribbon normally removed from the printing point and having a plurality of fields of different characteristics may be controlled so that it may, when the printing keys are actuated, be moved to cover the printing point with any desired field.

Although especially designed for the object stated, my invention may in addition be employed advantageously with ribbons of uniform character throughout in order to make use of substantially the entire width of such uniform ribbons.

My invention also includes means for throwing the ribbon out of operation, so that it does not cover the printing point at all when the keys are operated, for mimeograph work.

To the above and other ends the invention consists in the features of construction, combinations of devices and arrangements of parts hereinafter fully described and particularly pointed out in the claims.

I have shown my invention as applied to the Monarch typewriter, but it is to be understood that said invention may be adapted to other styles of writing machines.

In carrying out my invention in the present instance I substitute for the usual vibratory operating lever of the Monarch machine, which lever has a slot in its rear arm, an operating lever which is constantly connected at a fixed distance from its fulcrum with the upper end of a vertically disposed link. The lower end of said link is forked or bifurcated, the arms of the bifurcation being provided with openings which are adapted to co-operate with pins oppositely disposed on the central rearwardly extending arm of the usual pivoted universal bar frame, said pins being at different distances from the pivotal axis of said universal bar frame. I further provide a manually operated slide or cross-bar which

guides said link and controls its position transversely of the central arm of said frame. By adjusting the slide bar the forked link may be connected with one or another of the pins on the universal bar frame, so as to vary the throw of the ribbon carrier or may be entirely disconnected from said frame when it is desired to do mimeograph work.

In the accompanying drawings, Figure 1 is a vertical longitudinal sectional view of a typewriting machine, illustrating one form of my invention, parts of said machine being omitted. Figs. 2, 3 and 4 are enlarged fragmentary top plan views illustrating different relations between the forked link and the universal bar with which it is adapted to be connected and disconnected. Fig. 5 is a transverse vertical sectional view of the machine taken on a plane forward of the top plate, parts being omitted.

Referring more especially to Figs. 1 and 5 of the drawings, 1 designates the base of the machine from which rise corner posts 2 supporting a top plate 3. Key levers 4 are fulcrumed on a fulcrum plate 5 in the rear of the base, each key lever being provided with a restoring spring 6 and having pivoted to it at 7 a sub-lever 8. The lower end portion of each sub-lever is slotted to co-operate with a fixed abutment or fulcrum bar 9 and the upper end of each sub-lever is connected by a link 10 with a type bar 11. The type bars are pivoted in hangers 12 arranged in segmental series on a segmental type bar support 13. Said type bars are normally supported at their free end portions on a type rest 14 and are adapted, when their associate key levers are actuated, to co-operate with the front face of a platen 15 mounted in a carrier or carriage comprising side bars 16 joined at the rear by a slide bar 17, the latter being grooved at its top and bottom to co-operate with anti-friction balls 18. Said balls also co-operate with grooved guide rails 19 which are fixed to standards 20 rising from the top plate. The platen carriage carries a feed rack 21 which normally meshes with a feed pinion 22, the latter being operatively connected with a toothed escapement wheel 23. Feed dogs 24 co-operate with said escapement wheel, said dogs being mounted at the top of a pivoted vibratory dog carrier or rocker 25 having a horizontally disposed arm 26 which is connected by a link 27 with a cen-

tral extension or rearwardly extending arm 28 of a universal bar frame, the latter comprising also a rock shaft 29 pivoted on pivots 30 secured in the sides of the base. Side arms 31 extend rearwardly from the rock shaft 29 near its ends, said side arms and the central arm 28 being joined by a universal bar proper 32, the latter extending from side to side beneath the key levers 4. When one of the latter is operated the universal bar frame is swung downwardly on the pivots 30, causing the letter feeding or escapement devices to co-operate in a known manner to permit the carriage to be drawn a letter space distance 15 to the left under the influence of a spring drum 33 with which said carriage is connected by a band or strap 34.

A ribbon 35 is wound upon a pair of ribbon spools 36, one disposed horizontally at each 20 side of the machine forwardly of the platen and above the top plate. The ribbon is or may be divided into longitudinal stripes or fields *a* and *b* of different characteristics; that is to say, the field *a* may be of one color 25 and the field *b* of a different color—black and red respectively, for example—or the field *a* may be record ribbon and the field *b* copying ribbon. The ribbon may be fed longitudinally back and forth between the spools by 30 any suitable ribbon feeding mechanism, that shown in the drawings being the usual ribbon mechanism of the Monarch typewriter and comprising for each ribbon spool a beveled gear 37 operatively connected with its associate spool and meshing with a beveled pinion 38 at the forward end of a horizontal shaft 39, said shaft carrying at its rear end a beveled pinion 40. Each pinion 40 is adapted to mesh with a driving pinion 41 fixed to 35 40 a driving shaft 42, the latter being connected with and receiving motion from the spring drum 33 through two beveled gears 43 and 44, the construction being such that the shaft may be moved endwise without affecting 45 the connection between said gears. The endwise movement of the driving shaft operates to connect one or the other of the driving pinions 41 with its associate pinion 40 and to cause one or the other of the ribbon spools to 50 wind the ribbon thereon.

That portion of the ribbon which extends between the spools is normally held below the printing point by a vibratory ribbon carrier or ribbon vibrator 45 which is guided and 55 supported in the upright arms 46 of a guide bracket 47 secured by screws 48 to the top plate. The lower end or stem 49 of the vibrator is slotted and provided with a cross-pin 50 which co-operates with the slotted forward end of an operating lever 51 pivoted at 52 to a lug 53 depending from the top plate. The rear arm of the lever is perforated and receives a rivet 54 by which the lever is connected at a fixed distance from its fulcrum 60 with a connecting member or link 55. The

link depends from the rivet 54 and the lower portion of said link is flattened and forked or bifurcated to embrace loosely the central extension or arm 28 of the universal bar frame. One arm 56 of the bifurcation at the lower end of the link 55 lies at the right of the arm 28 and is provided with an engaging device or opening which is adapted to co-operate with an engaging device or pin 57 fixed to and extending laterally rightward from the 70 arm 28. The other arm 58 of the bifurcated portion of the link is offset rearwardly and toward the left, as shown in Figs. 1—4, and is then curved downwardly being provided with an engaging device or opening near its 80 lower end, said opening co-operating with an engaging device or pin 59 which is fixed to and extends laterally leftward from the arm 28 of the universal bar frame. The pin or engaging device 59 is at a greater distance 85 from the center of rotation of the universal bar frame than is the pin or engaging device 57, so that when the arm 58 is connected with its associate pin, the link 55 will receive a greater movement when the universal bar 90 frame is operated by the key levers than said link will receive when the arm 56 is connected with its associate pin. It will be noted from an inspection of Figs. 2—5 that the arms 56 and 58 are spread apart laterally so far that 95 when one arm is connected with its associate pin the other arm will be disconnected from its pin. The pin or rivet 54 is sufficiently loose to permit of the movement of the lower end portion of the link 55 transversely of the arm 28 to bring one or another of the engaging devices or openings at the lower ends of the arms 56 and 58 into co-operative engagement with the associate engaging devices or pins on said arm. The distance laterally between the arms 56 and 58 is such that when the link 55 has been shifted or moved transversely of the arm 28 about half of the distance of which said link is capable of being shifted, said link will be entirely disengaged 105 from the arm 28 as shown in Fig. 3 so that the universal bar frame may be actuated without affecting the link 55.

In order to shift the link 55 at will and to maintain it set in the desired position after it has been shifted, I provide means comprising a slide rod 60 arranged transversely of the machine above the key levers and supported near its ends in bearing openings in the sides of the base 1. About at its middle the slide 110 rod 60 is flattened as indicated at 61 and the flattened portion is formed with a slot or guide opening 62 which normally receives the lower flattened portion of the link 55 above the fork thereof. To facilitate assembling, the slot 62 has a wide circular portion 63 through which the rounded upper part of the link 55 may be passed from below before the upper end of said link is connected with the operating lever 51. The length of the slot 62 115

is slightly greater than the width of the flattened portion of the link so that the slight swinging movement to which said link is subjected in the operation of the machine may 5 not be interfered with. Outside the base frame the right-hand end of the slide rod 60 is provided with a finger button or cap 64 to enable it to be readily manipulated and inside the frame the right-hand end portion of 10 the slide rod has secured to it a collar 65 which prevents accidental withdrawal or removal of the slide rod from its place. The under side of the slide rod is provided with three notches or depressions 66, 67 and 68 15 which are co-operative with the free end of a spring detent 69 secured by screws 70 to the inner face of the right hand side of the base. The detent 69 co-operates with the notches in the slide rod to maintain it and through it 20 to the link 55, in any of the positions in which it may be desired to set the latter.

Referring now to the operation of the devices hereinbefore described, and assuming that the parts are arranged as in Fig. 5 with the detent 69 engaging with the right-hand notch 66, it will be seen that the slide rod is maintained in the leftmost of its adjusted positions. The parts are so constructed and arranged that this adjustment of the slide rod 30 causes an engagement between the opening in the arm 56 and the stud or pin 57 as shown both in Figs. 5 and 2. The pin 57 is arranged at such a distance from the pivotal axis of the universal bar frame that when the latter is 35 operated by any of the key levers the vibratory ribbon carrier will be thrown upward far enough to bring the upper field *a* of the ribbon opposite the printing point. The throw of the ribbon carrier will remain the 40 same as long as the actuating link is set as described and the type impressions will therefore follow in a path on the upper field *a* of the ribbon and longitudinally thereof. During the actuations of the universal bar frame 45 it will be understood that the link 55 is reciprocated in a general up and down direction, being guided by the opening or slot 62 in the flat portion 61 of the slide rod and being so controlled by the guide opening that it is prevented from moving laterally and thereby 50 changing its lateral relation with the central arm 28 of the universal bar frame.

When it may be desired to make use of the lower field *b* of the ribbon the slide rod 60 is 55 pulled longitudinally rightward until the notch 68 engages with the detent 69. This movement of the slide rod serves to shift or swing the lower end of the link 55 transversely of the arm 28 of the universal bar frame from 60 the position shown in Fig. 2 to that shown in Fig. 4. From an inspection of the latter figure it will be noted that the arm 56 has been disconnected from the universal bar frame and that the arm 58 is engaged with the pin 65 or engaging device 59. To facilitate the en-

gagement between the openings in the forked end of the link and the pins 57 and 59, the latter are preferably tapered at their ends, as shown for example in Fig. 4. With the arm 58 engaged with the pin 59, it will be seen 70 that the link 55 is thereby connected with the universal bar frame at a greater distance from the pivotal axis of the latter than before. The result is that an increased amount of movement is transmitted to the link 55 75 and through it to the vibratory ribbon carrier when the universal bar frame is operated, and consequently said ribbon carrier is thrown higher at said operation. The parts are so proportioned that the increased throw 80 of the ribbon carrier will bring the lower field *b* of the ribbon opposite the printing point, and as long as the link 55 is set as shown in Fig. 4 the throw or extent of movement of the carrier will remain the same and the type 85 impressions will follow in a path along the lower field *b* of the ribbon and longitudinally thereof.

When it is desired to dispense with the use of the ribbon, as in preparing a mimeograph 90 sheet, for example, the slide rod 60 is adjusted to bring the middle notch 67 into engagement with the detent 69. This movement of the slide rod swings the link to the position shown in Fig. 3, from an inspection of which 95 it will be seen that neither of the arms of said link is engaged with its associate pin so that said link is entirely disconnected from the central arm or member 28 of the universal bar frame and will not be affected by the operation 100 of the latter.

Various changes may be made without departing from the spirit and scope of my invention.

What I claim as new and desire to secure 105 by Letters Patent, is:—

1. In a typewriting machine, the combination of a vibratory ribbon carrier; operating means therefor including a link; a pivoted key-actuated universal bar frame having a central arm; and means for shifting said link at will transversely of said central arm in order to connect the link therewith at different distances from the pivotal axis of the universal bar frame and thereby vary 110 the throw of the ribbon carrier.

2. In a typewriting machine, the combination of a vibratory ribbon carrier; an operating lever therefor; an actuating link connected at one end with said operating 120 lever and bifurcated or forked at its other end; a pivoted key-actuated universal bar frame having a central arm embraced or straddled by the forked end of said link; and means for shifting said link to connect 125 one or another of the arms composing its fork with the central arm of the universal bar frame at different distances from the pivotal axis thereof in order to vary the throw of the ribbon carrier.

3. In a typewriting machine, the combination of a vibratory ribbon carrier; an operating lever therefor; an actuating link connected with and depending from said lever, said link terminating at its lower end in two arms arranged in different planes both fore and aft of the machine and transversely thereof; a pivoted key-actuated universal bar frame having a part arranged between the arms of said link; and means for connecting at will one or another of the arms of said link with said part of the universal bar frame at different distances from the pivotal axis of said frame in order to vary the throw of the ribbon carrier.

4. In a typewriting machine, the combination of a vibratory ribbon carrier; an operating lever therefor; an actuating link having a forked end, the arms comprising said forked end being provided with engaging openings; a pivoted key-actuated universal bar frame having a central arm embraced by the forked end of said link, said central arm having lateral oppositely disposed engaging pins at different distances from its fulcrum, each engaging pin being co-operative with one of the engaging openings in said link; and a slide bar for guiding and controlling said link, said slide bar being operative to shift said link to effect an engagement of one or another of its arms with the central arm of the universal bar frame.

5. In a typewriting machine, the combination of a vibratory ribbon carrier; an operating lever therefor; a pivoted key-actuated universal bar frame; a link connecting said universal bar frame with said operating

lever; means for shifting said link to engage with said universal bar frame at different distances from the pivotal axis of said universal bar frame, said link being also shiftable so as to be disengaged entirely from said universal bar frame.

6. In a typewriting machine, the combination of a vibratory ribbon carrier; an operating lever therefor; a pivoted key-actuated universal bar frame; a link connecting said universal bar frame and said operating lever; and means for varying the point of connection between said link and said universal bar frame and for disconnecting said link entirely from said universal bar frame.

7. In a typewriting machine, the combination of a vibratory ribbon carrier; an operating lever therefor; a link connected at one end with said operating lever and forked at its other end; a pivoted key-actuated universal bar frame having a part embraced or arranged between the arms composing the fork of said link; and means for shifting said link to engage one or another of its arms with the embraced part of said universal bar frame, said means being also operative to entirely disconnect said link from said universal bar frame.

Signed at the borough of Manhattan, city of New York, in the county of New York, and State of New York, this 6th day of October, A. D. 1906.
